UNITED STATES PATENT OFFICE.

OSCAR STODDARD, OF DETROIT, MICHIGAN.

KEY.

SPECIFICATION forming part of Letters Patent No. 399,094, dated March 5, 1889.

Application filed October 15, 1888. Serial No. 288,169. (No model.)

To all whom it may concern:

Be it known that I, OSCAR STODDARD, a citizen of the United States, residing at Detroit, in the county of Wayne and State of Michigan, have invented certain new and useful Improvements in Door-Keys; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This improved key is designed for the doors of residences having what is known as "mortise-locks."

The construction of this key is such that it cannot be tampered with when left in the lock by inserting a wire or tool through the key-hole from the outside of the door for the purpose of turning the key in the lock and thereby unlocking the door.

The key is so constructed that a portion remains fixed in the key-hole of the lock when locking or unlocking the door. This stationary portion fills the outer opening or escutcheon of the key-hole, thereby preventing the insertion of any tool through the key-hole when the door is locked and the key is in the lock.

The essential features of this invention will be fully hereinafter set forth, and pointed out particularly in the claim.

In the accompanying drawings, forming a part of the specification, Figure 1 is a side plan of an ordinary door-lock, showing the turned portion of the key by dotted lines when the door is locked, showing also the stationary portion of the key in the key-hole. Fig. 2 is a side plan of my improved key. Fig. 3 is a slight modification of same. Fig. 4 is a view, partly in section, showing the parts of the key detached and their relative position.

In the drawings, *L* represents the lock-case, and *d* the key-hole therein, in which *n* represents the portion of the key that remains stationary as the key is turned in the lock to move the lock-bolt, as in locking and unlocking the door. The shank *S* of the key is pro-

vided with a slot or opening, *f*, which leads from near the annular shoulder *h* to about the center of the stem or shank. Communicating with the oblong opening *f*, and extending through the head *H* of the key, is an opening or hole, *t*, which hole receives the metal rivet *Z*. (See Fig. 4.) Said rivet has the head *a'*, which lies within the opening *f*, as shown in Figs. 2 and 3.

D represents the common lock-operating wing to the key, which may be of any desired shape.

Mounted on the outer end of the rivet *Z*, which projects through the head of the key, is an auxiliary wing, *n*, its form in cross-section coinciding with that of the head *H* and operating-wing *D* of the key. The auxiliary wing *n* is provided with the hole *t'* in its outer end, being countersunk at *a*. Said hole registers with the hole *t* in the head of the key. The rivet *Z* is upset at *e*, thereby holding the auxiliary wing in position, and by the upsetting of said rivet the desired tension may be obtained, so as to hold the auxiliary wing in its normal position, so as to register with the wing *D* of the key, whereby when the key is passed into the key-hole of the lock it will enter freely, allowing the auxiliary wing *n* to pass into and fill the key-hole on the opposite face of the lock, and to remain therein as the balance of the key is rotated to move the lock-bolt, for the purposes before stated.

In Fig. 3 I show the wing *n* provided with a rear extension or prong, *V*, which allows the wing *D* to rotate above it. This prong acts as a guide to prevent the wing *n* from catching when withdrawing the key from the key-hole. This feature is not essential, for the reason that the wing *n* will remain in its proper position if the rivet *Z* is properly tightened by the upsetting of the end at *e*, as before stated. This arrangement affords means of giving to the auxiliary wing *n* a proper degree of pressure or friction, whereby the parts will work complete, and the auxiliary wing is firmly and substantially secured to the head of the key.

Having thus fully set forth my invention, what I claim as new, and desire to secure by Letters Patent, is—

A door-key comprising the following ele-

ments: the shank having the opening therein, the head having the annular shoulder and wing, said parts formed integral, the hole passing through the head and communicating with the opening in the shank, the auxiliary wing, its form in cross-section coinciding with the head and wing of the key and having the hole therein, and the rivet passing through

the head and the auxiliary wing, its outer end being upset, as and for the purposes specified. 10

In testimony whereof I affix my signature in presence of two witnesses.

OSCAR STODDARD.
